UNITED STATES PATENT OFFICE.

MICKEL MARC, OF BLOOMINGTON, ILLINOIS.

DESIGN FOR BOOKCASE, WRITING-DESK, AND PHOTO-DISPLAYING CABINET.

40,436.

Specification for Design.

Patented Jan. 11, 1910.

Application filed September 14, 1909. Serial No. 517,728. Term of patent 14 years.

To all whom it may concern:

Be it known that I, MICKEL MARC, a citizen of the United States, residing at Bloomington, in the county of McLean and State of Illinois, have invented a new, original, and Ornamental Design for Bookcase, Writing-Desk, and Photo-Displaying Cabinet, of which the following is a specification, reference being had to the accompanying drawing, forming part thereof.

The figure is an elevation showing my new design.

I claim:

The ornamental design for a book case, writing desk and photo displaying cabinet as shown.

MICKEL MARC.
